UNITED STATES PATENT OFFICE

147,807

DESIGN FOR A DRY SHAVER

Herbert E. Page, Dayton, Ohio

Application February 23, 1946, Serial No. 126,854

Term of patent 14 years

(Cl. D22—3)

To all whom it may concern:

Be it known that I, Herbert E. Page, a citizen of the United States and resident of the city of Dayton, in the county of Montgomery and State of Ohio, have invented a new, original, and ornamental Design for a Dry Shaver, of which the following is a specification, reference being had to the accompanying drawings, forming part thereof, and in which:

Fig. 1 is a perspective view of a dry shaver, showing my new design;

Fig. 2 is a top plan view thereof;

Fig. 3 is a side elevational view thereof;

Fig. 4 is a bottom plan view thereof;

Fig. 5 is a front elevational view thereof; and

Fig. 6 is a rear elevational view thereof.

The characterizing features of the design

consist in the portions shown in full lines in the drawings.

What is claimed is:

The ornamental design for a dry shaver, substantially as shown and described.

HERBERT E. PAGE.
